[57] CLAIM

The ornamental design for a shoe sole, substantially as shown and described.

DESCRIPTION

FIG. 1 is a left side elevational view of a shoe sole showing my new design;

FIG. 2 is a right side elevational view thereof;

FIG. 3 is a bottom plan view thereof;

FIG. 4 is a front elevational view thereof;

FIG. 5 is a rear elevational view thereof.

The top of the shoe sole, not shown, is substantially plain and unornamented.
